UNITED STATES PATENT OFFICE.

JOHN HAYLE ROUSE AND ALBERT MOORE DE LIGNE, OF SAN FRANCISCO, CALIFORNIA,
ASSIGNORS TO WILLIAM ALBERT CALVIN, OF SAN FRANCISCO, CALIFORNIA.

PET-COCK OPENING AND CLOSING DEVICE.

1,402,254.

Specification of Letters Patent. Patented Jan. 3, 1922.

Application filed January 25, 1921. Serial No. 429,313.

To all whom it may concern:

Be it known that we, JOHN HAYLE ROUSE and ALBERT MOORE DE LIGNE, citizens of the United States, and residents of San Francisco, county of San Francisco and State of California, have invented a new and useful Pet-Cock Opening and Closing Device, of which the following is a specification.

The present invention, while relating in general to attachments or accessories for automobiles, has reference more particularly to a tool or device for opening and closing petcocks or the like which are ordinarily located in more or less inaccessible places on the motor of the automobile, but which must be opened and closed at certain times for testing or otherwise ascertaining the condition of the lubricant supply of the automobile.

In its preferred embodiment the invention is intended to be associated with petcocks situated in the crank case of an automobile engine or in the transmission case. As an example of the application of the invention the accompanying drawing illustrates the advantages of the same used as an attachment of Ford automobiles, in which it is associated with the customary pair of petcocks located in the base of the transmission case and used, in most instances, as a means of testing the level of the oil supply. In carrying out the test by means of these petcocks, the level of the oil may be ascertained by opening one or the other, and it is extremely inconvenient to open and close the same due to their inaccessible location. The device proposed by the present invention includes as one of its salient features a relatively long manipulating tool which is maintained operatively associated with one of the petcocks and with the manipulating handle of the tool terminating where it may be easily and conveniently actuated for opening or closing the petcock.

One of the objects of the invention, aside from the advantages above mentioned, is to produce a device or tool which may be manufactured at a comparatively low cost, easily applied, and capable of carrying out its intended use with the greatest of efficiency.

Inasmuch as there are two of these petcocks to be opened and closed when occasion arises, and as they are positioned in close proximity one to the other, a further object of the invention is to so arrange the device

that it may be shifted from one petcock to another for selectively opening or closing either of the two.

With these and further objects in view, a detailed description will now follow with reference to the figures in the drawing, in which Figure 1 is a view in side elevation and partly in section of the front part of a motor vehicle, including the engine, and showing the invention as applied in use; Figure 2 is a detail view in plan showing the application of the invention, and Figure 3 is a perspective view of the device apart from the automobile.

Considering the motor vehicle to have the conventional type of engine A, crank case B and transmission casing C, with the customary oil well D arranged as a single casting between the crank case B and the base of the transmission casing C, the oil supply should be kept at a certain level in the well, and for the purpose of testing the level of the same, petcocks D¹ and D² are arranged in the well and are adapted to be opened or closed for the purpose stated.

In opening or closing these petcocks without the use of the present invention it is necessary to reach under the car, which is extremely inconvenient.

The device or tool for opening or closing the petcocks includes a relatively long rod (5) one end of which carries a socket (6) which is adapted to fit over the flattened end of the valve stem, with the opposite end of the rod terminating in a hand grip or handle (7). As a convenient means of mounting or attaching the device it is preferred to use a bracket made from a single piece of strap metal such as (8) one end of which has an opening through which the rod (5) passes, with the opposite end twisted so that the flat portion is bent horizontally and with the extreme end thereof bent inwardly at right angles to the straight part, and including an opening as at (9). This bracket may be attached on the under side of the running board, with one of the bolts which connects the fender to the running board passing through the opening (9), as best shown in Figures 1 and 2. The end of the inwardly presented part of the bracket may abut against the flange of the fender to add rigidity to the structure.

To maintain the socket (6) in engagement with the petcock a suitable coil spring (10)

may encircle the rod (5) with the same confined between the bracket (8) and a pin (11) which passes through the rod; the tendency of the spring being to push the rod inwardly

5 and hold the socket in engagement with the petcock, so that the jar or vibration incident to the travel of the vehicle will not disengage the device.

As previously stated, it sometimes happens 10 that it is desirable to open the lower one of the petcocks, to which end the opening in the bracket (8) through which the rod passes is made slightly larger than the diameter of the rod, so that an outward pull may be imposed 15 to the rod to overcome the influence of the spring (10) and disengage the socket (6); whereupon the rod may be dropped down to engage the lower one of the petcocks. In this way the device is really interchangeable 20 to selectively open or close either one of the petcocks.

It should be noted that the socket (6) is made in a novel manner in that it includes a flat piece of metal stamped out and bent 25 upon itself, as best shown in Figure 3.

As mentioned above, the device would seem best applicable to Ford automobiles; at the same time, the invention should not be construed as limited to this particular use,

as its advantages may be realized in other instances where like results are to be accomplished.

We claim:

A device of the class described comprising a relatively long rod having a socket formed 35 at one end, said socket comprising an oblong shaped cap produced from a single strip of sheet metal, the opposite side edges of said strip being first cut out to leave ears at the four corners of the strip and then bent upon 40 itself to provide said cap and with the ears bent inwardly in confronting position to close the top and bottom of the cap, the opposite end of said rod terminating in a hand grip, a bracket strap having a relatively 45 large opening through which the rod extends for supporting the device on an automobile, the attaching end of the strap being twisted and bent at right angles with a bolt opening 50 therein made to receive a running board bolt of the automobile and with the bent end of the strap adapted to bear against a flange on the fender of the automobile, and a coiled spring on the rod adapted to maintain the socket in engagement with a valve stem.

JOHN HAYLE ROUSE.
